(57) **CLAIM**

The ornamental design for a weight rack crossmember, as shown and described.

DESCRIPTION

FIG. 1 is a top, front, right perspective view of a weight rack crossmember showing my new design;

FIG. 2 is a bottom, front, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top, front, right perspective view of the weight rack crossmember of FIGS. 1-8, shown with example environment in the form of a device mounted on the weight rack crossmember;

FIG. 10 is a bottom, front, right perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines immediately adjacent to the shaded area define the bounds of the claimed design and form no part thereof. The broken lines depicting the remainder of the weight rack crossmember and the example environment in FIGS. 9-16 form no part of the claimed design.

1 Claim, 16 Drawing Sheets
